CLAIM

The ornamental design for a dropper for a sampling container, as shown and described.

DESCRIPTION

FIG. 1 is a left, front and top perspective view of a dropper for a sampling container according to a first embodiment; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; and FIG. 8 is a sectional view thereof along line 8-8 of FIG. 6.

FIG. 9 is a left, front and top perspective view of a dropper for a sampling container according to a third second embodiment,

FIG. 10 is a front elevational view thereof,

FIG. 11 is a rear elevational view thereof,

FIG. 12 is a left side elevational view thereof,

FIG. 13 is a right side elevational view thereof,

FIG. 14 is a top plan view thereof,

FIG. 15 is a bottom plan view thereof; and,

FIG. 16 is a sectional view thereof along line 16-16 of FIG. 14.

The broken lines shown in the drawings illustrate portions of the dropper for a sampling container that form no part of the claimed design. The dot-dash broken lines represent the boundaries of the claim and form no part thereof.
